United States Patent Office.

MATTHEW FALOON, OF BLOOMINGTON, ILLINOIS.

Letters Patent No. 101,600, dated April 5, 1870.

IMPROVED SPRING-BED BOTTOM.

The Schedule referred to in these Letters Patent and making part of the same.

To all whom it may concern:

Be it known that I, MATTHEW FALOON, of Bloomington, in the county of McLean, and in the State of Illinois, have invented certain new and useful Improvements in Spring-Bed Bottoms; and do hereby declare that the following is a full, clear, and exact description thereof, reference being had to the accompanying drawings and to the letters of reference marked thereon making a part of this specification.

The nature of my invention consists in so constructing and arranging the springs on bed-bottoms that the weight upon the same will be at all times equalized; that is, in such manner if a heavy person is lying on one side side and a light one or none at all on the other side the springs will nevertheless give equally and keep the bed level; or, in other words, I transfer the excess of weight, on whichever side it may be, to the opposite side.

In order to enable others skilled in the art to which my invention appertains to make and use the same, I will now proceed to describe its construction and operation, referring to the annexed drawings, in which—

Figure 1 is a plan view, and

Figure 2, a longitudinal vertical section of a bedstead with my improved bed-bottom therein.

A represents the bedstead, made in any desired size and shape, within which fits the bed-bottom frame B.

In the bed-bottom frame B are three cross-bars, one at the head and one at the foot, both marked C in the drawing, and another, D, in or rather under the center of the frame.

The bed-slats E E, which run lengthwise in the frame B, are connected at their center on the under side by a cross-slat, G, and a suitable distance from their ends by leather straps H H.

Each slat E is at each end connected with the cross-bar C in the following manner:

Upon the bar C is secured a wire spring, I, formed of one piece of wire, bent in the center so as to form a projecting tongue or loop, a, fastened by means of a staple, i. The wire is then bent so as to form two coils e e, and the ends extend inward and form hooks, which are fastened in a leather piece, J, secured to the under side of the seat E.

Upon the cross-bar D are placed and firmly secured the large ends of a series of spiral springs, K K, the smaller ends of which are secured to and support the cross-slat G.

Under the center of the bar D is pivoted a lever, L, which, by rods M M, is connected with the outside slats E.

The center springs K K prevent the bed-slats E from sinking down in the middle of the bed and resting on the cross-bar.

The rods M M with pivoted the lever L equalize the weight of a heavy person with a light one in the same bed.

The weight of the heavy person will push down the rod under him and draw down the other side; by the pushing on one end of the lever back, brings the other end forward, thus causing a child to lie level with a heavy person, and the springs under the light person will move with as much ease as those under the heavy person.

The attachments and springs at the ends of the bed-slats E are without any pole through the springs, for the purpose of making better springs, which will spring without binding on such pole as in others, and consequently make no place for bedbugs. Also, the leather attachment will bear down at both sides of each slat and hold them level, and, besides, will not make a joint at the ends of the slats, as with all others.

Having thus fully described my invention,

What I claim as new, and desire to secure by Letters Patent, is—

The combination of the bed-slats E E, leather pieces J J, springs I I and K K, connecting-rods M M, and lever L, all constructed and arranged as described to operate substantially in the manner and for the purposes herein set forth.

In testimony that I claim the foregoing, I have hereunto set my hand this 24th day of November, 1869.

MATTHEW FALOON.
